Attorney

UNITED STATES PATENT OFFICE.

WILL A. CLARK, OF ST. LOUIS, MISSOURI.

DAUBER PAD FOR LIQUID-POLISH APPLIERS.

Application filed December 13, 1927. Serial No. 239,754.

This invention relates to dauber pads for liquid polish appliers and more particularly to a device of this character which is adapted to be employed as a permanent adjunct of a tube or container for the polish.

An important object of the invention is to provide a construction of this character which may be very cheaply and readily manufactured and attached to the container, so that when the contents of the container have become exhausted, it may be thrown away.

A further object of the invention is to provide a device of this character which, while capable of being very cheaply constructed, provides a construction such that it is capable of ready operation to enable its use with liquids of different consistencies and provides a construction such that a soft and neat polish applying dauber is provided.

These and other objects I attain by the construction shown in the accompanying drawing, wherein for the purpose of illustration is shown a preferred embodiment of my invention and wherein:—

Figure 1 is a vertical sectional view showing a dauber pad constructed in accordance with my invention applied to a polish container;

Figure 2 is a section on the line 2—2 of Figure 1;

Figure 3 is an elevation with the dauber pad removed;

Figure 4 is a plan of the fabric pad employed;

Figure 5 is a side elevation of the felt strip.

Referring now more particularly to the drawing, the numeral 10 generally designates the wall of a polish container and 11 the dauber pad applied thereto. This dauber pad in accordance with my invention comprises a central substantially cylindrical core 12, which may be of any suitable material. This core, where employed with liquid polish, has preferably applied thereto at the outer end thereof a spreader 13, consisting of a disk which may be either integral with or attached to the tube and which has at its periphery openings 13^a. The disk is at present shown as secured to the tube by bending tabs 13^b formed thereon against the outer face of the tube. The tube is likewise preferably provided with outstanding tangs 14, which may be disposed at any convenient point along the outer wall of the tube.

In combination with this core, I employ a strip of felt 15, which is of greater width than

the length of the core and which, at a point spaced from the end of the strip a distance equal to or slightly greater than the circumference of the core, is slit, as at 16, from one edge to a point adjacent to but slightly spaced from the opposite edge. I also provide a gauze pad 17 which may consist of a plurality of layers of gauze, the number of layers and the texture of the gauze depending upon the polish with which the pad is to be employed. If the pad is to be employed with liquid polish, the gauze should be closely woven and a greater number of layers of gauze employed than where the polish is of a thick creamy or pasty consistency.

The felt pad 15 is applied to the core in such manner that the unslit edge of the strip substantially coincides with the inner end of the cylinder and is wound about the cylinder 75 to the split 16. The gauze pad 17 is then applied and the binding of the felt continued. The felt may be held in its applied position either by stitching 18 or any other suitable means. In the present instance in Figure 1, 80 I have shown the container 10 as provided upon the end thereof with which the pad engages with tangs 19 engaging the exterior of the pad to hold the felt in position, while in Figure 3, stitching is employed for this 85 purpose. In some instances, where the polish is unusually thin, the space provided within the felt binding between the gauze pad and the outer end of the core may be filled with gauze padding.

The projection of the felt binding beyond the end of the core provides a cushion for the core, preventing the same from either injuring the surface being treated or hurting the foot. The construction whereby a portion 95 of this felt binding is arranged within the gauze insures at least against this portion of the felt flaring outwardly, so that the cushioning effect would be destroyed and the core exposed.

I have found that in a dauber constructed in this manner, the polish will be transferred from the container to the surface to which polish is being applied as fast as the surface can receive the polish by absorption, and yet will not feed liquid to a surface which will not absorb it. For this reason, the dauber, when abutted by a metallic cover (not shown), will not pass the polish, and at the same time, will hold the polish ready for immediate application. Attention is directed to the fact that by slitting the felt strip as

shown, a single felt strip is enabled to produce both the inner and outer felt bindings employed.

Since the construction hereinbefore set forth is capable of a certain range of change and modification without materially departing from the spirit of the invention, I do not limit myself to such specific structure except as hereinafter claimed.

10 I claim:

1. In a dauber for polish applicers, a tubular core, an inner felt binding surrounding said core and having its edge projected beyond the outer end of the core, a gauze pad 15 extending across the mouth of the tube thus provided and having its edges folded about said felt binding, an outer felt binding surrounding the edges of the gauze pad and means for securing the end of said outer felt 20 binding in position.

2. In a dauber for polish applicers, a tubular core, an inner felt binding surrounding said core and having its edge projected beyond the outer end of the core, a gauze pad 25 extending across the mouth of the tube thus provided and having its edges folded about said felt binding, an outer felt binding surrounding the edges of the gauze pad, and means for securing the end of said outer felt binding in position, the inner and outer felt 30 bindings comprising a single strip slit intermediate its edges and at a point from the inner end thereof a distance at least equal to the circumference of the core, the core having tangs engaging said inner binding.

3. In a dauber for polish applicers, a tubular core, an inner felt binding surrounding said core and having its edge projected beyond the outer end of the core, a gauze pad 40 extending across the mouth of the tube thus provided and having its edges folded about said felt binding, an outer felt binding surrounding the edges of the gauze pad, and means for securing the end of said outer felt binding in position, the core being secured to 45 the inner binding.

4. In a dauber for polish applicers, a tubular core, an inner felt binding surrounding said core and having its edge projected beyond the outer end of the core, a gauze pad 50 extending across the mouth of the tube thus provided and having its edges folded about said felt binding, an outer felt binding surrounding the edges of the gauze pad, and means for securing the end of said outer 55 felt binding in position, the inner and outer felt bindings comprising a single strip slit intermediate its edges and at a point from the inner end thereof a distance at least equal to the circumference of the core, and a spreader plate at the outer end of the core.

the circumference of the core, the core being secured to the inner binding.

5. In a dauber for polish applicers, a tubular core, an inner felt binding surrounding said core and having its edge projected beyond the outer end of the core, a gauze pad 60 extending across the mouth of the tube thus provided and having its edges folded about said felt binding, an outer felt binding surrounding the edges of the gauze pad, and means for securing the end of said outer felt binding in position, the core having tangs engaging said 65 inner binding.

6. In a dauber for polish applicers, a tubular core, an inner felt binding surrounding said core and having its edge projected beyond the outer end of the core, a gauze pad 70 extending across the mouth of the tube thus provided and having its edges folded about said felt binding, an outer felt binding surrounding the edges of the gauze pad, and means for securing the end of said outer felt binding in position, the inner and outer felt 75 bindings comprising a single strip slit intermediate its edges and at a point from the inner end thereof a distance at least equal to the circumference of the core, the core having tangs engaging said inner binding.

7. In a dauber for polish applicers, a tubular core, an inner felt binding surrounding said core and having its edge projected beyond the outer end of the core, a gauze pad 80 extending across the mouth of the tube thus provided and having its edges folded about said felt binding, an outer felt binding surrounding the edges of the gauze pad, and means for securing the end of said outer felt binding in position, the inner and outer felt 85 bindings comprising a single strip slit intermediate its edges and at a point from the inner end thereof a distance at least equal to the circumference of the core, the core having tangs engaging said inner binding.

8. In a dauber for polish applicers, a tubular core, an inner felt binding surrounding said core and having its edge projected beyond the outer end of the core, a gauze pad 90

extending across the mouth of the tube thus provided and having its edges folded about said felt binding, an outer felt binding surrounding the edges of the gauze pad, means for securing the end of said outer felt binding in position, and a spreader plate at the outer end of the core.

9. In a dauber for polish applicers, a tubular core, an inner felt binding surrounding said core and having its edge projected beyond the outer end of the core, a gauze pad 100 extending across the mouth of the tube thus provided and having its edges folded about said felt binding, an outer felt binding surrounding the edges of the gauze pad, means for securing the end of said outer felt binding in position, the inner and outer felt 105 bindings comprising a single strip slit intermediate its edges and at a point from the inner end thereof a distance at least equal to the circumference of the core, and a spreader plate at the outer end of the core.

10. In testimony whereof I hereunto affix my signature.

WILL. A. CLARK.
